CLAIM

(57) The ornamental design for a portion of a work machine, as shown and described.

DESCRIPTION

FIG. 1 is a top, front, left perspective view of a portion of a work machine embodying our new design;

FIG. 2 is a left side elevational view thereof; and,

FIG. 3 is a right side elevational view thereof.

The broken line representations in the figures show unclaimed environment or boundaries, and thus form no part of the claimed design.
